UNITED STATES PATENT OFFICE

HARRY T. ABOLIN, OF HASBROUCK HEIGHTS, NEW JERSEY, ASSIGNOR TO LINCRUSTA-WALTON COMPANY, OF HACKENSACK, NEW JERSEY, A CORPORATION OF NEW JERSEY

DESIGN FOR WALL COVERING OR SIMILAR ARTICLE OF MANUFACTURE IN SHEET FORM

Application filed September 14, 1928. Serial No. 28,138. Term of patent 3½ years.

To all whom it may concern:

Be it known that I, HARRY T. ABOLIN, a citizen of the United States, and a resident of Hasbrouck Heights, county of Bergen, State of New Jersey, have invented a new, original, and ornamental Design for Wall Covering or Similar Article of Manufacture in Sheet Form, of which the following is a specification, reference being had to the accompanying drawing, forming part thereof, wherein the figure is a plan view of a piece of wall covering showing the design in the form of a unit which is capable of being repeated lengthwise of the sheet to any extent desired.

I claim:

The ornamental design for wall covering or similar article of manufacture in sheet form substantially as shown and described.

HARRY T. ABOLIN.
